SURFACING MACHINE

John Clarence Inman, Windsor, Ontario, Canada, assignor to Lempeo Products, Inc., Bedford, Ohio, a corporation of Ohio

Application June 27, 1939, Serial No. 281,425

20 Claims. (Cl. 51—151)

My invention relates to improvements in surfacing machines for surfacing or resurfacing the gasket engaging faces of cylinder heads or blocks, the faces of clutch pressure plates, and other surfaces which it is desired to grind true.

An object of my invention is to devise a machine which will hold the work, a surface of which is to be ground, exerting pressure thereon to press it down against an abrasive plate and move it over such plate to effect the grinding operation.

A further object is to devise a machine which will impart to the work combined longitudinal and lateral movement so that the path travelled by any point in the work will be in the form of a figure eight for each cycle of movement.

And a still further object is to provide means, in the case where the machine is to be used for grinding the surfaces of clutch pressure plates, whereby in addition to the figure eight movement a progressive rotary motion will be imparted to the work.

With the above and other objects in view which will hereinafter appear as the specification proceeds, my invention, in its preferred embodiment, consists in the construction and arrangement hereinafter more particularly described and illustrated in the accompanying drawings in which:

Fig. 1 represents a side view of the machine with the near side removed to expose the drive and abrasive plate to view.

Fig. 2 is a plan view thereof.

Fig. 3 is an inverted sectional plan view taken on the line 3—3 (Fig. 1).

Fig. 4 is an enlarged end elevational view showing the mechanism for imparting the lateral movement to the work (in this case a cylinder head) illustrated in dotted lines.

Fig. 5 is a similarly enlarged plan view of the mechanism shown in Fig. 4.

Fig. 6 is an end elevational detail (drawn to a slightly larger scale than Figs. 1 and 2) illustrating the mechanism for imparting progressive rotary motion to the work.

Fig. 7 is a horizontal section taken on the line 7—7 (Fig. 6).

Fig. 8 is a horizontal section taken on the line 8—8 (Fig. 6).

Fig. 9 is a similar section to that shown in Fig. 8 only illustrating the parts in different positions.

Fig. 10 is an enlarged inverted plan view of

the mechanism for imparting progressive rotary motion to the work, and

Fig. 11 is an enlarged vertical section taken through the line 11—11 (Fig. 7).

Like characters of reference indicate corresponding parts in the different views of the drawings.

Where the machine is to be used for surfacing or resurfacing clutch pressure plates the mechanism for imparting progressive rotary motion to the work is incorporated therewith as well as the mechanism for imparting the figure eight movements whereas where the machine is intended for use for grinding cylinder heads or blocks only the mechanism for imparting the figure eight movements is employed and the mechanism for imparting progressive rotary motion to the work is omitted.

I will first describe the machine which includes all the mechanism necessary to surface or resurface a cylinder head or block.

A table 12 is provided having a planary top 13 preferably covered by a sheet of resilient material 14 such as sponge rubber. The abrasive plate 15 rests on the sheet 14 and may assume the form described and claimed in my co-pending application Serial No. 279,890, filed June 19, 1939, for improvements in Cylinder head and block surfacing plates in which the plate is covered by a band of abrasive material such as emery cloth.

Upwardly extending flanges 16 are provided on the table 12 to properly position the abrasive plate 15.

The mechanism for imparting the figure eight movements to the work, whether clutch pressure plate or cylinder head or block, comprises spaced apart slide rods 17 longitudinally disposed under the table top and supported at their ends in spaced relation thereto in the depending brackets 18. A slide 19 is reciprocable on the rods 17 and standards 20 extend upwardly from the sides of the slide at the sides of the table.

Blocks 21 having depending sockets 22 receive the upper portions of the standards 20 and have spaced laterally disposed slide rods 23 extending transversely from block to block, said blocks being vertically adjustable on the standards and held in any adjusted position by the set screws 24.

A slide 25 is provided between blocks 21 and is adapted to be reciprocated on the slide rods 23, said slide having an aperture 26 therethrough extending to the vicinity of one end thereof, which aperture terminates at its inner end in

a throat 27 of reduced width. An upwardly directed extension 28 is provided on the slide 25 in the vicinity of its end remote from the aperture 26, said extension and throat 27 being preferably located on the longitudinal centre line of the slide. A bracket 29 provided at one end with a socket 30 located over the aperture 26 has its other end provided with a longitudinal slot 31 adapted to receive the flattened upper end 32 of a pin 33 which extends down freely through the extension 28 and slide 25 and protrudes below the latter through a double armed member 34 which is held thereon by a nut 35 threaded onto the lower end of such pin 33, said pin being a driving fit in the member 34. The bracket 29 is held on the upper end of the pin 33 by a bolt 36 threaded thereinto.

The socket 30 on the bracket 29 has a vertical spindle 37 threaded therethrough and extending downwardly into the vicinity of the work. The lower end of the spindle is provided with a stiff spiral spring 38 which, at its lower extremity, carries a flanged member 39 provided with a hardened steel point 40 adapted to engage the work A or B (illustrated in dotted lines in Figs. 4 and 5 as a cylinder head and in full lines in Figs. 1 and 2 as a clutch pressure plate). A lock nut 41 is provided on the spindle 37 adapted to engage the upper end of the socket 30 and the upper end of such spindle terminates in a knob 42 for facilitating rotation thereof.

The double armed member 34 provided with opposed arms 43 having longitudinal slots 44 therethrough is provided with an extension 45 extending inwardly substantially perpendicularly to the arms. Such extension carries at its free extremity an upwardly directed pin 46 adapted to extend up through the throat 27 in the slide aperture 26 and protrude thereabove. A pawl 47 pivoted on the upper end of the pin 46 is adapted to engage a ratchet wheel 48 rotatably mounted on the slide 25 between the extension 28 and the throat 27, said pawl being spring-held against the ratchet wheel by a spring 49, one end of which is attached to the upper end of the pin 46 and the other end to the pawl. An additional spring-held detent 50 similar to the above pawl and spring is provided on the slide 25 engageable with the ratchet wheel 48 to prevent retrograde rotation thereof when the pawl 47 is ratcheting as will hereinafter appear.

A crank 51 curved to escape the spindle 37 is pivoted at one end by a stud 52 to the ratchet wheel 48 in the vicinity of its periphery and at its opposite end by a bolt 53 to a clamp adjustably mounted on the slide rods 23, said clamp comprising upper and lower members 54, 55 secured together by the bolt 53 upon the lower end of which a nut 56 is threaded.

Where the machine is used for grinding cylinder heads, for instance, headed studs 57 extend down through the slots 44 in the arms 43 of the member 34 into the bolt holes of the cylinder head, said studs 57 being shouldered and capable of being adjusted in the slots to accommodate themselves to different spacing between bolt holes and having stepped lower extremities to enable them to be inserted into bolt holes of different diameters. Such studs 57 are secured in position in the slots by the nuts 58.

The upwardly extending standards 20 are secured to the slide 19 by a transverse strap 59 bolted thereto and having its ends provided with holes into which the lower threaded ends of the

standards are inserted and held in place by the nuts 60.

The slide 19 is reciprocated by any suitable mechanism and prime mover as, for instance, by an electric motor 61 attached to a bed 62 which may be clamped to the slide rods 17, the motor having an armature shaft pulley 63 connected by a belt 64 to a shaft pulley 65 of a reduction gear 66 mounted beneath the top of the table 12 and which includes a power take-off crank 67 pivotally connected at its free end to one end of a link 68 which is pivotally connected at its other end to the slide 19.

The mechanism as above described is all that is required for imparting the necessary movement to cylinder heads and blocks to surface or resurface their gasket engaging faces. Where, however, the machine is to be used for grinding the face of a clutch pressure plate the latter is held in position relatively to the actuating mechanism by other means which will hereinafter be described and in addition to the figure eight motion of the work to be ground means is provided for progressively rotating the clutch pressure plate.

Instead of the studs 57 which are not used, a member 69, as illustrated a forked member, is attached to the double armed member 34 by headed bolts 70 extending through the slots 44 into the free extremities of the legs of the member 69, said latter member straddling the extension 45 but positioned below the same.

At the junction of the legs of the member 69 an orifice 71 is provided to receive loosely the head 72 of a stud 73 of a chuck employed to hold the clutch pressure plate in position while grinding its face. Such loose connection between the chuck stud and member 69 constitutes a pivotal connection enabling the chuck and attached work to align itself with the abrasive plate. Such chuck may be of any orthodox form and as illustrated consists of a cylindrical casing 74 having radial jaw guideways 75 in its bottom adapted to receive the outwardly movable jaws 76 disposed therein, said jaws adapted to extend through orifices in the casing side wall and to engage the inner periphery of the clutch pressure plate which is designated as A. The upper faces of the jaws 76 are provided with transverse curved teeth 77 inserted into a spiral rack 78 on the lower face of a disc 79 disposed concentrically in the casing 74, said disc having radially disposed teeth 80 in its upper surface engageable with pinions 81 on horizontal stubs 82 journaled in the casing side wall and extending to the exterior face thereof. The outer ends of the stubs are of socket form to receive a key (not shown). A flanged plate 83 fits inside the casing 74 above the disc 79 and has notches 84 in its flange which straddle the reduced portions 82a of the stubs 82 to prevent the latter being displaced inwardly or outwardly. The flanged plate 83 has a depending central boss 85 resting on the bottom of the chuck casing. The hereinbefore mentioned stud 73 is disposed axially of the chuck by being mounted on a cover plate 86 which is secured to the wall of casing 74 by the screws 87. The cover plate is of greater diameter than the casing and its periphery is provided with a toothed rack 88.

A depending stud 89 is provided on the slide 25 by having its upper end inserted into an orifice 90 therein and held in place by a set screw 91. A pawl 92 is pivoted on the lower end of the stud 89 and is spring-held against the toothed

rack 88 by a spiral spring 93 attached at one end to the pawl and at the other end to the stud.

In order to provide longer jaws in the case where the inner periphery of the clutch pressure plate or ring is of excessive diameter, as illustrated in Figure 10 the jaws 76 may have extensible portions 76a secured to the jaws proper by screws 94.

I will now describe the operation of my machine in so far as the grinding of a cylinder head is concerned, reference being had particularly to Figs. 4 and 5 of the drawings, it being understood that the clutch pressure plate holding chuck and the means for supporting it and rotating it have been removed.

The abrasive plate 15 as illustrated or any other suitable form of abrasive plate is placed in position on the table 12 as shown and the cylinder head designated by B is placed thereon, the slide 25 and its attached mechanism having previously been raised on the standards 20 sufficiently to enable the abrasive plate and cylinder head to be placed in position. The slide 25 and its attached mechanism are now lowered until the studs 57, having been suitably adjusted in the slots 44, are inserted into the bolt holes in the cylinder head B. The set screws 24 are then screwed in to lock the blocks 21 on the standards. By loosening the clamps for the crank 51 the cylinder head and the slide 25 can be suitably adjusted for proper lateral centering, the clamp for the crank 51 being then tightened on the slide rods 23. Subsequently the spindle 37 is screwed down in the socket 38 by the knob 42 until the hardened point 40 engages the upper surface of the cylinder head and the spring 38 exerts sufficient pressure thereon to press the surface to be ground of the cylinder head against the abrasive plate.

The electric motor 61 is then switched on and through the medium of the pulleys 63 and 65 and belt 64 the reduction gearing 66 is operated and its crank 67 is rotated with the result that the longitudinal slide 19 is reciprocated by the crank connected link 68. As the work to be ground, i. e., the cylinder head B is connected to the longitudinal slide 19 through the standards 20, lateral slide rods 23, lateral slide 25, double armed member 34 and studs 57 on its arms 43, the work is reciprocated longitudinally upon the reciprocation of the longitudinal slide 19.

Simultaneously during each longitudinal reciprocation the work is also moved laterally, this occurring upon the longitudinal movement of the work in the direction indicated by the arrow X in Fig. 5. Owing to the lag of the work due to the friction of its surface to be ground on the abrasive plate and the pressure exerted by the spring 38, such work tends to turn about a point underlying the pivot pin 33 in the direction of the arrow Y in Fig. 5. This is due to the offsetting of the pivot pin 33 from the longitudinal centre line of the work. As this occurs the member 34 attached to the work swings in the same direction until the stud 46 engages a side wall of the throat 27 which limits such swinging movement. During such swing the pawl 41 on the stud 46 engaging the ratchet wheel 48 rotates the same in a counter-clockwise direction and actuates the crank 51 with the result that the slide 25 and attached work is moved laterally.

During the longitudinal movement of the work in the reverse direction to that indicated by the arrow X in Fig. 5, the work tends to turn in

the reverse direction to that indicated by the arrow Y in Fig. 5 with the result that the member 34 is swung back in such direction until the stud 46 engages the opposite side wall of the throat 27. During such swing the pawl merely ratchets on the ratchet wheel 48 and no lateral movement is imparted to the lateral slide 25 and therefore to the work.

The result of such combined longitudinal and lateral movement of the work including the swing thereof is that any point of the work will during a complete cycle of such movements describe a figure eight path. Owing to the fact that on each longitudinal reciprocation of the work the lateral movement thereof is comparatively small it will take several longitudinal reciprocations for the work to travel completely across the abrasive plate in either direction. Thus successive figure eight paths described by any point in the work will not register but will be progressively positioned across such plate.

Consequently owing to the combined movements imparted to the work as its surface is ground against the abrasive plate, such ground surface will be in a true plane.

In the case where it is desired to grind the surface of a clutch pressure plate A as illustrated in Figs. 1 and 2 the studs 57 are not used and the clutch pressure plate holding mechanism above described is employed. In so far as the combined longitudinal and lateral movements imparted to the work by the slides 19 and 25 are concerned these are identical to the above case in which the cylinder head surface is ground but, in addition, the clutch pressure plate is progressively rotated. Each time the clutch pressure plate A commences its longitudinal stroke in the direction of the arrow X in Fig. 5 owing to the lag of the work and the offsetting of the pivot pin 33 the member 34 is turned in the direction of the arrow Y as above described with the result that the relative position of the lateral slide 25 and clutch pressure plate holding chuck are altered, the slide 25 being advanced with respect to the chuck. As the pawl 92 is positioned on the slide 25, during such lag of the work and the chuck the pawl 92 engaging the rack 88 on the chuck will turn the chuck a limited extent and consequently equivalently rotate the clutch pressure plate. On the reverse longitudinal stroke the pawl 92 merely ratchets on the rack. The disposition of the parts of the mechanism effecting such operations are shown in Figs. 8 and 9 wherein the latter figure illustrates the relative movement of member 34 and chuck to effect the turning of the latter and the former figure shows their relative positions on the reverse longitudinal stroke.

What I claim as my invention is:

1. In a machine for truing plane surfaces on cylinder heads and blocks and on clutch pressure plates, the combination with an abrasive surface upon which the work to be ground rests, of a longitudinally reciprocable slide, means for reciprocating the slide, means attached to the slide for holding the work pivotally from a point offset from its longitudinal centre line, said work reciprocating longitudinally on the abrasive surface with the longitudinal reciprocation of the slide, and means for moving the work laterally on the abrasive surface during each cycle of longitudinal reciprocation thereof.

2. In a machine for truing plane surfaces on cylinder heads and blocks and on clutch pressure plates, the combination with an abrasive surface

upon which the work to be ground rests, of a longitudinally reciprocable slide, means for reciprocating the slide, means attached to the slide for holding the work pivotally from a point offset from its longitudinal centre line, said work reciprocating longitudinally on the abrasive surface with the longitudinal reciprocation of the slide, and means actuated by the swinging of the work about the pivot point at the beginning of one stroke in the cycle of longitudinal reciprocation for moving the work laterally on the abrasive surface.

3. A machine as claimed in claim 2 wherein the means for moving the work laterally comprises a laterally movable slide to which the work is pivotally connected, means for mounting the lateral slide on the longitudinally reciprocable slide, and means attached to the mounting means and the lateral slide for actuating the latter upon the swinging of the work about its pivot point in one direction.

4. A machine as claimed in claim 1 wherein means is provided for progressively rotating the work during each cycle of longitudinal reciprocation thereof, said means being actuated by the swinging of the work about its pivot point in one direction.

5. In a machine for truing plane surfaces on cylinder heads and blocks and on clutch pressure plates, the combination with an abrasive surface upon which the work to be ground rests, of a longitudinally reciprocable slide, means for reciprocating the slide, means attached to the slide for holding the work pivotally from a point offset from its longitudinal centre line, said work reciprocating longitudinally on the abrasive surface with the longitudinal reciprocation of the slide, means actuated by the swinging of the work about the pivot point at the beginning of one stroke in the cycle of longitudinal reciprocation for moving the work laterally on the abrasive surface, and means for progressively rotating the work simultaneously with each lateral movement thereof on the abrasive surface.

6. A machine as claimed in claim 2 wherein the means for moving the work laterally comprises a laterally movable slide to which the work is pivotally connected, means for mounting the lateral slide on the longitudinally reciprocable slide, means attached to the mounting means and the lateral slide for actuating the latter upon the swinging of the work about its pivot point in one direction, a rotatable chuck incorporated in the work holding means for attaching the work thereto, and means on the lateral slide for progressively rotating the chuck during each lateral movement of the work.

7. A machine for truing plane surfaces on cylinder heads and blocks and on clutch pressure plates comprising a table, an abrasive surface on said table upon which the work rests, a longitudinally movable slide on said table, means for reciprocating said slide, a laterally movable slide, means for mounting the lateral slide on said longitudinal slide, a double armed member pivotally connected to the lateral slide, means for attaching the work to the double armed member in such position that its longitudinal centre line is offset laterally from the pivot of such double armed member for permitting the work to swing a limited extent at the beginning of each stroke of the longitudinal slide, and a crank pivoted on said lateral slide mounting means and operatively connected to the lateral slide for actuating the lateral slide and move the attached work lat-

erally at the beginning of one stroke of the longitudinal slide.

8. A machine for truing plane surfaces on cylinder heads and blocks and on clutch pressure plates comprising a table, an abrasive surface on said table upon which the work rests, a longitudinally movable slide on said table, means for reciprocating said slide, a laterally movable slide, means for mounting the lateral slide on said longitudinal slide, a double armed member pivotally connected to the lateral slide, means for attaching the work to the double armed member in such position that its longitudinal centre line is offset laterally from the pivot of such double armed member for permitting the work to swing a limited extent at the beginning of each stroke of the longitudinal slide, a crank pivoted on said lateral slide mounting means and operatively connected to the lateral slide for actuating the lateral slide and move the attached work laterally at the beginning of one stroke of the longitudinal slide, and resilient means on the lateral slide for exerting pressure on the work for pressing it against the abrasive surface.

9. A machine as claimed in claim 7 wherein the lateral slide has a slot therethrough, and the double armed member has a lateral extension, and a stud on the extension extending into the slot for limiting the swing of the double armed member and the attached work.

10. A machine as claimed in claim 7 wherein the lateral slide has a slot therethrough, and the double armed member has a lateral extension, a stud on the extension extending into the slot for limiting the swing of the double armed member and the attached work, a ratchet wheel rotatably mounted on the slide, one end of the crank being pivotally connected to the ratchet wheel in the vicinity of its periphery, and a spring-held pawl on the stud engageable with the ratchet wheel.

11. A machine as claimed in claim 8 wherein the means on the lateral slide for exerting pressure on the work comprises a bracket pivotally connected to the lateral slide and including a socket on its free end, a vertical spindle threaded through the socket, a spring on the lower end of the spindle, and a pointed member on the spring adapted to engage the work.

12. A machine as claimed in claim 8 wherein a pivot pin extends through the slide for pivotally mounting the double armed member thereon, said pin being non-rotatable in the member, a bracket non-rotatably mounted at one end on the pivot pin and including a socket on its free end, a vertical spindle threaded through the socket, a spring on the lower end of the spindle, and a pointed member on the spring adapted to engage the work.

13. A machine as claimed in claim 7 wherein the means for attaching the work to the double armed member comprises a forked member, the legs of which are secured to the arms of the double armed member, a rotatable chuck attached to the work and rotatably mounted on the forked member, and means in the lateral slide for progressively rotating the chuck at each reciprocation of the longitudinal slide and attached work.

14. A machine as claimed in claim 7 wherein the means for attaching the work to the double armed member comprises a forked member, the legs of which are secured to the arms of the double armed member, a rotatable chuck attached to the work and rotatably mounted on the

forked member, a peripheral rack on the chuck, a depending stud on the lateral slide, and a spring-held pawl on the stud engageable with the rack for progressively rotating the chuck at each reciprocation of the longitudinal slide and attached work.

15. In a device of the character described, a polishing surface, and means pivotally attached to the work offset from the longitudinal center of the work for reciprocating the same in contact with said surface whereby the work will pivot relatively to said means upon each reciprocating stroke, movable means for moving said work laterally throughout a cycle of reciprocations, and a member carried by said work and moving said movable means at each pivotal movement of said work.

16. In a machine for truing plane surfaces on cylinder heads and blocks and on clutch pressure plates, the combination with a base and an abrasive surface supported thereby, of means for holding the work to be ground in grinding position on said surface, means for reciprocating such work relative to said base and longitudinally upon said surface, said reciprocating means including means movable laterally relative to said reciprocating means and connecting said work to said reciprocating means, coacting means carried by said laterally movable means and said reciprocating means and operative upon each longitudinal reciprocation to impart lateral movement to said work relative to said base, whereby said work is moved progressively across said surface in a lateral direction upon successive cycles of longitudinal reciprocation, and means for simultaneously and progressively rotating said work upon said surface upon successive cycles of reciprocation thereof.

17. In a machine for truing plane surfaces on cylinder heads and blocks and on clutch pressure plates, the combination with a base and an

abrasive surface supported thereby, of means for holding the work to be ground in a grinding position on said surface, means for reciprocating said work relative to said base and longitudinally upon said surface, said reciprocating means including means movable laterally relative to said reciprocating means, offset pivotal means connecting said work to said laterally movable means to permit oscillatory movement of said work in each cycle of reciprocation thereof, and co-acting means carried by said offset means, said laterally movable means and said reciprocating means and operative upon the oscillatory movement of said work in at least one direction to move said laterally movable means and said work laterally of said surface.

18. The machine of claim 17, and said co-acting means including means for continuing said lateral movement of said work in a step-by-step manner throughout a plurality of cycles of reciprocation of said work.

19. The machine of claim 17, and additional co-acting means carried by said offset means and said reciprocating means and operative automatically to progressively rotate said work upon said surface upon successive cycles of reciprocation thereof.

20. In a device of the character described, the combination with a stationary abrasive surface, of slide means for longitudinally reciprocating an article across said surface, a second laterally directed slide means carried by said first slide and connecting the latter to said article, means for imparting step-by-step lateral movement to said second slide and article throughout a cycle of longitudinal reciprocations, and coacting means carried by said article and first slide of imparting step-by-step rotation to said article throughout said cycle of reciprocations.

JOHN CLARENCE INMAN.
